UNITED STATES PATENT OFFICE.

BASIL J. YANCHENKO, OF NEW YORK, N. Y., ASSIGNOR, BY MESNE ASSIGNMENTS, TO
LIBERTY NATIONAL BANK, TRUSTEE, OF SYRACUSE, NEW YORK.

IRONING-PRESS BURN GUARD.

Application filed February 6, 1925. Serial No. 7,238.

This invention relates to laundry ironing presses and the like and more particularly relates to improvements in burn guards for protecting the operator from being accidentally burned by the hot exposed polished metal face of the ironing head or buck.

A further object of the invention is to produce an automatically operating burn guard in the form of a flat member adapted to cover the hot metal ironing surface of the machine when open and this device may assume the form of a roller curtain which is designed to be drawn across the face of the ironing member as the press opens up and which similarly moves back away from the face of the member to expose its polished ironing face directly to the work when the ironer closes down upon the goods.

Among other things, a purpose of this invention is to produce an improved gear or chain driven automatic burn guard curtain for the purpose aforesaid but it is understood how certain changes may be made in construction and operation without departing from the principle of the invention.

The accompanying drawings illustrate an embodiment of the invention wherein,—

Figure 1 shows a side view of a conventional type ironing press in open position with the burn guard member drawn across the upper exposed face of the pressing member.

Figure 2 illustrates a detailed side elevation of the ironing press in closed position showing the burn guard member removed from between the closing ironer jaws in order that the work may be directly treated by the exposed metal ironing head face.

Figure 3 shows an underneath fragmentary view of the head looking up against the polished face thereof, and this view is taken on the line 3—3 of Figure 2.

Figures 4 and 5 illustrate an improved curtain operating means in the form of a chain suspended to engage the main drive pinion and take the place of the gear rack 23 hereinbefore described.

Referring further to the drawings for a more detailed description of the invention, there is shown an ironing machine frame 10 with a press lever 11 pivoted thereon at 12 and provided with any suitable operating means such as a pedal 13 pivoted at 14 in the frame having an upstanding bell crank 55 or toggle link 15. A toggle link 16 is suit-

ably connected to the toggle link 15 and to the press lever 11 which enables the operator to close the ironing head 17 down upon the ironing buck 18 supported by the frame 10. The buck is usually covered with a canvas 60 or cloth 19 and for that reason the hot steam heated buck 18 is protected and will not accidentally burn the operator's hand while spreading the work thereon, but the head 17 must necessarily carry an exposed 65 hot metal ironing surface 21 to impart a domestic finish and gloss to the work. My improved burn guard for ironing presses of conventional type just described may be manufactured in the form of an attachment 70 and installed on pressing machines in use, and this burn guard automatically operates to cover and uncover the exposed polished metal face 21 of the press head in order that it may effectively cooperate with the 75 cloth covered ironing member 18.

By way of explaining the principle of my invention and one form of structure thereof, there is shown a stationary gear rack 23 suitably anchored in this instance to the 80 frame. One gear rack 23 is sufficient though two may be employed if desired by placing one at each end of the pressing members 17 and 18. A shaft 24 carries a driven gear 25 anchored to the shaft and meshing with 85 the gear rack 23 which rotates the said gear 25. Each end of the shaft 24 is fitted with a sprocket 26 anchored thereto. A support bracket 27 is fixed to each end of the press head 17 and the aforesaid shaft 24 is journaled in these two brackets 27 and the brackets serve to hold the shaft in proper position with the one gear 25 in mesh with the rack 23 and so it follows that an up and down motion of the head 17 subjects the gear 25 90 and the two sprockets 26 to rotation.

Front brackets 29 are fixed to each front corner end of the press head 17 and these brackets journal a shaft 30. A sprocket wheel 31 is anchored to each end of the 100 shaft 30 and a suitable light weight chain 32 is carried on both sets of sprocket wheels 26 and 31 which provides two parallel spaced chains 32. This arrangement places a chain 32 at each end of the pressing head 17 and this chain serves to draw a burn guard back and forth across the head pressing face 21 and the guard may consist of a roll-up curtain or other means.

One of the operating shafts as 24 or 30 110

is adapted to carry the aforesaid burn guard curtain and in this instance a curtain drum 34 is shown freely mounted on the front shaft and adapted to undergo slight rotary motion relatively to the shaft 30. Though this shaft is carried freely in the drum 34, a spring 38 encircles the shaft 30 and has one end thereof anchored to this shaft at 28 and the other end fixed to the drum at 22. Thus the shaft and drum are connected together by the spring only which acts something like a flexible key. The shaft, being the original driving member, drives the drum through the spring because the spring is installed under a torsion strain sufficient to exercise a driving relation over the shaft.

The innermost end of a curtain 35 is attached to the drum as is done with any ordinary roller curtain device. The outer free end of the curtain 35 is attached to a draw rod 36 which is preferably made somewhat longer than the width of the curtain 35 so as to reach out beyond the brackets 29 and be attached as at 37 at each end thereof to the chains 32. It follows that the traveling motion of the chains 32 cause the curtain 35 to unroll from and roll back upon the curtain drum 34 and the spring 38 acts to keep the curtain tautly drawn. This improved construction in the spring connection existing between the shaft and drum removes strain from the spring which exists in ordinary curtain roller devices because the spring is not called upon to wind up the curtain for the chains 32 perform both functions, the rolling up and unrolling curtain action.

In operation, the ironing machine operator depresses the pedal 13 which brings the two ironing jaws 17 and 18 together. This downward head movement initiates counter clockwise rotation of the drive pinion 25 which causes the lower section of the chain 32 to move forwardly towards the operator thereby causing the burn guard curtain 35 to be wound upon the drum 34 by the pulling movement of the chain which uncovers the ironing surface 21 thereby permitting direct engagement of the bare metal ironing face 21 with the work upon the buck 18. After the ironing operation is completed the operator may depress the kick-off pedal 40 which causes the toggle 15-16 to be broken rearwardly thereby allowing the press head 17 to rise, the result of which is to reverse the direction of the chain movement thereby driving the curtain 35 across the ironing face 21 to cover it up and protect the operator's hand while the press jaws are open.

This improved burn guard protective member shown in Figures 4 and 5 automatically moves across the ironing surface 50 as the ironing head 51 rises and automat-

ically moves back away therefrom as the ironer closes in order that the hot exposed ironing surface may directly engage the work and impart a gloss or domestic finish to the laundered goods.

The construction of the drum, the use of the mounting brackets for the shafts, and the mounting of the chains, in fact the assembly of the structure may be the same as the assembly already hereinbefore described, the point of the difference being that I employ a flexible chain 53 which is passed over a main drive pinion 54. The upper end of the chain is anchored at 55 to a frame bracket 56 and the other end of the chain is preferably connected to a tension spring 57 which in turn is fastened to the frame at 58.

The spring 57 serves to hold the chain 53 in positive engagement with the drive pinion 54 in order that this pinion drive a shaft 60. A sprocket 61 is fixed to the shaft 60 and a chain 62 is passed over the sprocket 61 as well as being passed over a sprocket 63 fixed to a shaft 64 and adapted to drive a curtain drum 65. A curtain 66 is rolled upon the drum with its outer edge fastened to the chain as at 67.

Thus in operating the last described form of the invention shown in Figures 4 and 5, it follows that an up and down motion of the head 51 causes the drive pinion 54 to traverse the flexible suspended chain 53 which causes the curtain 66 to roll back away from and uncover the ironing surface 50 as the jaw 51 closes down on the work. Similarly, as the jaw opens, the drive pinion 54 acts to again draw the curtain 66 back across the ironing face to protect the operator from being burned while working about the machine.

What I claim is:

1. An ironing press comprising in combination, cooperating ironing jaws provided with an exposed ironing surface, means to open and close the jaws, a burn guard protective member mounted on the press, gear drive means to move the burn guard back and forth across the exposed ironing surface, and means arranged to automatically drive the gear means during the opening and closing of the jaws.

2. An ironing press comprising in combination, cooperating ironing jaws provided with an exposed ironing surface, means to open and close the jaws, a burn guard protective member mounted on the press, gear drive means to move the burn guard back and forth across the exposed ironing surface, and a gear rack mounted on the press meshing with the gear drive means to automatically actuate the burn guard as the jaws open and close.

3. An ironing press comprising in combination, cooperating ironing jaws provided

with an exposed ironing surface, means to open and close the jaws, a burn guard protective member mounted on the press, gear drive means to move the burn guard back and forth across the exposed ironing surface, a chain cooperating with the gear means and adapted to travel back and forth in relation to the exposed ironing surface, means connecting the burn guard to the chain, and means to automatically drive the gear means as the jaws open and close.

4. An ironing press comprising in combination, cooperating ironing jaws provided with an exposed ironing face, means to open and close the jaws, chains carried on one of the jaws, means to actuate the chains, and a burn guard member carried on the jaw with the chains and fastened to the chains.

5. An ironing press comprising in combination, cooperating ironing jaws provided with an exposed ironing face, means to open and close the jaws, chains carried on one of the jaws, means to actuate the chains, a drum rotated by the chain, and a curtain carried on the drum and fastened to the chain.

6. An ironing press comprising in combination, cooperating ironing jaws adapted to open wide and close upon the work and having an exposed ironing face, means to open and close the jaws, a drum carried by one of the jaws, a curtain carried on the drum, a chain arranged to rotate the drum, and means to automatically drive the chain when the jaws open and close.

7. An ironing press comprising in combination, cooperating ironing jaws adapted to open wide and close upon the work and having an exposed ironing face, means to open and close the jaws, a drum carried by one of the jaws, a curtain carried on the drum, a chain arranged to rotate the drum, and a cooperating rack and pinion adapted to automatically drive the chain.

8. An ironing press comprising in combination, cooperating ironing jaws having an exposed ironing face, means to open wide the jaws and close the same, sprocket wheels, a drum carried on one of the jaws and rotated by the sprocket wheels and chain, a curtain mounted on the drum, and a rack and pinion adapted to drive the chain and sprocket wheels.

9. An ironing press comprising in combination, cooperating wide opening ironing jaws, means to open and close the jaws, a pair of shafts which are mounted on the front and rear edges of one of the jaws, sprocket wheels carried by the shafts, chains on the sprockets, a drum carried on one of the shafts, and a burn guard mounted on the drum and attached to the chain, and means to drive the shafts.

10. An ironing press comprising in combi-

nation, cooperating wide opening jaws, means to open and close the jaws, a pair of shafts which are mounted on the front and rear edges of one of the jaws, sprocket wheels carried by the shafts, chains on the sprockets, a drum carried on one of the shafts, a burn guard mounted on the drum and attached to the chain, and a yieldable connecting device serving to connect the drum to the shaft but allowing relatively rotatory motion thereon, and means to drive the shafts.

11. An ironing press comprising in combination, cooperating ironing jaws, means to open and close the jaws, a shaft carried on one jaw, a drum journaled on the shaft, flexible means connecting the shaft and drum together whereby the shaft rotates the drum, a burn guard curtain carried on the drum and rolled up and unrolled by the rotation of the shaft driving through the flexible means, and means for operating the shaft.

12. An ironing press comprising in combination, cooperating ironing jaws, means to open and close the jaws, a shaft carried on one jaw, a drum journaled on the shaft, flexible means connecting the shaft and drum together whereby the shaft rotates the drum, a burn guard curtain carried on the drum and rolled up and unrolled by the rotation of the shaft driving through the flexible means, means for operating the shaft, and means cooperating with the aforesaid jaw opening and closing means whereby the curtain is drawn off the drum as the jaws open and rolled back on the drum as the jaws close.

13. An ironing press comprising in combination, cooperating ironing jaws adapted to open wide and close upon the work and having an exposed ironing face, means to open and close the jaws, a drum carried by one of the jaws, a curtain carried on the drum, a chain arranged to rotate the drum, and means engaging the pinion serving to revolve said pinion as the press opens and closes.

14. An ironing press comprising in combination, cooperating ironing jaws having an exposed ironing face, means to open wide the jaws and close the same, sprocket wheels, a drum carried on one of the jaws and rotated by the sprocket wheels and chain, a curtain mounted on the drum, and means engaging the pinion serving to revolve said pinion as the press opens and closes.

15. An ironing press comprising in combination, cooperating ironing jaws adapted to open wide and close upon the work and having an exposed ironing face, means to open and close the jaws, a drum carried by one of the jaws, a curtain carried on the drum, a chain arranged to rotate the drum, a drive pinion adapted to operate the chain, and a chain having its ends attached to the frame and remaining stationary and engaging the drive pinion.

16. An ironing press having a frame and comprising in combination, cooperating wide opening ironer jaws with an exposed polished metal surface carried thereby to impart a domestic finish to the laundered goods, means to open and close the jaws, a burn guard protective curtain carried on the press, curtain operating means fixed to the curtain and adapted to actuate the curtain back and forth across the exposed jaw ironer surface, 10 a drive pinion associated with the curtain operating means, and a device suspended upon the press frame engaging the drive pinion.

In testimony whereof I affix my signature.
BASIL J. YANCHENKO.
